W. M. GOODWIN

VALVE OPERATING MECHANISM FOR INTERNAL COMBUSTION ENGINES

Filed April 26, 1926

UNITED STATES PATENT OFFICE.

WILLIAM M. GOODWIN, OF CENTRAL SQUARE, NEW YORK.

VALVE-OPERATING MECHANISM FOR INTERNAL-COMBUSTION ENGINES.

Application filed April 26, 1926. Serial No. 104,646.

This invention relates to a valve operating mechanism for internal combustion engines of the class set forth in my Patents 1,270,941, July 2, 1918, and 1,500,556, July 8, 1924, and 1,577,965, March 23, 1926, in so far that the main object is to maintain uninterrupted connection between each spring closed poppet valve and its lifting means so that all of the parts necessary to the operation of the valve may move freely yet positively with a minimum lost motion and thereby to render such operation substantially noiseless.

The present invention, however, relates more particularly to the use of a take-up wedge between the valve stem and its operating cam adjustable about an axis parallel with and at one side of the axis of the valve and having a slightly angular adjustment about said axis to compensate for variations in the length of the valve stem due to varying temperatures and wear in a manner somewhat similar to that set forth in my Patent 1,577,965.

The main object of the present invention is to provide means for effecting a positive angular movement of the wedge against the action of a suitable retracting spring to assure a positive seating of the valve by its retracting spring at the proper time without breaking the connection between the cam and valve stem.

Other objects and uses relating to specific parts of the device will be brought out in the following description.

In the drawings:

Figure 1 is a vertical sectional view, partly in elevation, of a poppet valve and its operating mechanism together with adjacent portions of the frame of an internal combustion engine, the valve being shown in a position just about to close.

Figure 2 is a sectional view taken in the plane of line 2-2, Figure 1.

Figures 3 and 4 are horizontal sectional views taken in the planes of lines 3-3 and 4-4 respectively, Figure 1.

Figure 5 is a side elevation, partly in section of a portion of a slightly modified form of my invention.

Figure 6 is a plan on a small scale of the developed cam for effecting a positive angular motion of the wedge in reverse directions.

This device is adapted to be used more particularly in connection with a poppet valve —1— of an internal combustion engine —2— in which the valve —1— is opened and closed to and from its seat —3— by means of a cam —4— and a retracting spring —5— respectively.

The valve —1— and its retracting spring —5— may be of any well-known construction but as shown the valve stem is reciprocally movable in a guide —6— in the engine frame —2— while the spring —5— is interposed between the upper end of the guide —6— and a suitable washer seat —7— on a portion of the stem underlying the guide —6—.

The cam —4— may also be of any well-known construction capable of opening the valve —1— against the action of its retracting spring —5— once during each revolution.

Lost motion take-up.

Suitable means is provided for maintaining uninterrupted connection between the cam —4— and valve stem as —1'— to prevent lost motion and thereby to render the valve operating means substantially noiseless.

For this latter purpose a cylindrical member —8— is mounted for reciprocal axial and angular movement in a suitable guide bearing —9— on the engine frame between the cam —4— and lower end of the valve stem —1'— with its axis at one side of and parallel with the axis of the valve stem which latter is preferably arranged directly over the axis of the cam shaft as —4'—.

That is, the cylindrical member —8— is preferably tubular and offset transversely of the axes of the cam shaft —4'— and valve stem —1'— a distance sufficient to bring one side thereof in a direct line between said axes for transmitting lifting motion from the cam —4— to the valve against the action of the retracting spring —5—.

The cylindrical member —8— is preferably composed of lower and upper co-axial sections —8'— and —8''—, the lower section —8'— being provided at its lower end with an offset bearing member —10— resting upon the perimeter of the cam —4—.

The upper section —8''— is journaled in and upon the upper end of the section —8'—

and is provided with an offset inclined bearing or wedge surface —11— on its upper end face and at the same side of its axis as the lower bearing member —10— for engaging the lower end face of the valve stem —1'—, said wedge surface being elongated circumferentially for maintaining contact with the lower end of the valve stem during the limited angular movement of the member —8'— and —8''—.

The bearing member —10— and wedge surface —11— are arranged in a direct line between the axes of the cam shaft —4'— and valve stem —1'—, the lower face of the bearing member —10— being convexed transversely of the shaft to maintain a line contact with the cam —4— in all positions of rotation of the cam surface.

A pair of cam flanges —12— are rigidly secured to the cam shaft —4'— co-axial therewith and at opposite ends of the cam —4— and also at opposite sides of the lower end of the bearing member —10— with which they are adapted to engage.

The inner faces of these flanges —12— are provided with more or less abrupt cam surfaces —13— and —13'— in axial alignment and inclined in the same direction thereby forming between them what may be termed a cam groove of substantially the same axial length as the corresponding width of the offset bearing member —10— so that the cam surfaces —13— and —13'— may ride against opposite faces of the bearing member —10— during the rotation of the cam shaft in the direction indicated by arrow —x—, Figures 1 and 2.

These cam surfaces —13— and —13'— are parallel and gradually return circumferentially from their high points to the lower points as indicated as in Figure 5, the high points of said cam surfaces being arranged nearly opposite the high point of the cam —4— or at the lower end of said cam and in such relation thereto as to cause a slight turning movement of the wedge surface —11— toward the upper end of the incline to register a lower point of the wedge with the adjacent end of the valve stem and thereby to assure the complete crossing of the valve at the proper time or immediately following the lifting of the valve by the high point of the cam.

The portion of the periphery of the cam —4— opposite its high point and immediately following the high points of the cams —13— and —13'— are concentric with the axis of the cam shaft to allow the valve to dwell in its closed position during the fuel intake and period of combustion if it is the exhaust valve or during the exhaust and period of combustion if it is the intake valve.

The opposite side faces of the bearing member —10— are preferably convexed

transversely of the shaft —4'— to assure line contacts with the cam surfaces —13— and —13'— and also to permit those cam surfaces to ride freely past the bearing member during the rotation of the cam shaft.

Suitable means is provided for automatically turning the wedge member —8'— about its axis in the direction of its lost point to maintain contact between the wedge surface —11— and lower end of the valve stem and for this purpose a coiled spring —14— is attached at one end to a post —15— on the upper end face of the section —8— and has its other end attached to another post —16— which is secured with the periphery of the section —8'— and is adapted to move in a circumferentially elongated recess —17— in the inner wall of the bushing or bearing —9— as shown in Figures 1 and 2.

The construction shown in Figure 4 is similar to that shown in Figures 1 to 3 inclusive except that the lower face of the section —8'— and upper face of the section —8— are provided with cooperative adjacent wedge surfaces —19— and —19'— which are elongated circumferentially.

In this latter construction the cam flanges —12— are spaced a relatively shorter distance apart than those shown in Figures 1 and 3 while the offset member —10— projecting between said cam flanges is correspondingly narrower.

Operation.

Assuming that the cam shaft —4'— is moving in the direction indicated by arrow —x—, Figures 1 and 2, and that the high point of the cam has just passed from under the bearing member —10— and that the cam surfaces —13— and —13'— are just about to engage the adjacent faces of the bearing member —10— under which conditions the valve —1— will be slightly open.

Then as the cam surfaces —13— and —13'— register with opposite sides of the bearing member —10— the engagement of the cam surface —13— with the corresponding side of said bearing member will effect a corresponding angular movement of the tubular member —8— in the direction indicated by arrow —y—, Figures 1 and 3, thereby causing a lower point of the wedge surface —11— to register with the adjacent end face of the valve stem to allow a corresponding lowering of the valve to its seat by the action of the spring —5—, it being understood that this angular motion transmitted to the wedge member —8'— is due to the fact that the end thrust friction between the members —8— and —8'— is somewhat greater than the friction between the wedge surface —11— and adjacent end of the valve stem when the point of contact is shifting to a lower part of the wedge sur-

face during which time the contact between the wedge surface —11— and valve stem is maintained by the tension spring —14—.

Now as the cams —4— and —13— and —13'— complete one revolution the remaining portions of the cam surfaces of the members —12— effect an angular movement of the member —8'— in the opposite direction thereby placing the spring —14— under additional tension to assure the maintenance of contact of the wedge surface —11— with the lower end of the valve stem.

The operation of the members —8'— and —8''— by the cam surfaces —13— and —13'— is similar to that previously described except that the wedge surfaces —19— and —19'— produces a slightly quicker release on the return movement of the section —8'— which release is instantly followed by the angular rotation of the member —8''— by the spring —14— to assure a continuous connection between the cam —4— and valve stem and thereby preventing lost motion and noise incidental thereto.

What I claim is:—

1. The combination with a spring closed poppet valve of an internal combustion engine, a cam shaft, a cam on the shaft, means actuated by the cam for opening the valve including a wedge engaging the valve stem, a second cam on the shaft, and means actu-

ated by the last-named cam for moving the wedge in the direction of its inclination.

2. The combination with a cam shaft and a spring closed valve of an internal combustion engine, a cam on the shaft, means for maintaining operative connection between the cam and valve including a wedge and a second cam on the shaft for moving the wedge in the direction of its inclination.

3. The combination with a cam shaft and a spring closed valve of an internal combustion engine, a cam on the shaft, means for maintaining operative connection between the cam and valve including a wedge movable about an axis parallel with and at one side of the axis of the valve, and means rotating with the shaft for effecting an angular movement of the wedge in the direction of its inclination.

4. The combination with a cam shaft and a spring closed valve of an internal combustion engine, of a cylindrical member supported in radially offset relation to the axis of the valve stem and provided with a wedge surface in contact with the valve stem at one side of its axis, a cam on the shaft, and means actuated by the cam for effecting an angular movement of the cylindrical member and wedge carried thereby.

In witness whereof I have hereunto set my hand this 15 day of April 1926.

WILLIAM M. GOODWIN.
